(57) **CLAIM**

The ornamental design for a biometric sensor, as shown and described.

DESCRIPTION

FIG. 1 is a front and top side perspective view of a biometric sensor showing a first embodiment of our new design; FIG. 2 is a first side view of the biometric sensor of FIG. 1; FIG. 3 is a second side view of the biometric sensor of FIG. 1;

FIG. 4 is a third side view of the biometric sensor of FIG. 1;

FIG. 5 is a top side view of the biometric sensor of FIG. 1; FIG. 6 is a bottom side view of the biometric sensor of FIG. 1;

FIG. 7 is a fourth side view of the biometric sensor of FIG. 1;

FIG. 8 is a front and top side perspective view of a biometric sensor showing a second embodiment of our new design; FIG. 9 is a first side view of the biometric sensor of FIG. 8; FIG. 10 is a second side view of the biometric sensor of FIG. 8;

FIG. 11 is a third side view of the biometric sensor of FIG. 8; FIG. 12 is a top side view of the biometric sensor of FIG. 8; FIG. 13 is a bottom side view of the biometric sensor of FIG. 8; and,

FIG. 14 is a fourth side view of the biometric sensor of FIG. 8.

(Continued)

The broken lines depict portions of a biometric sensor that form no part of the claimed design.
